AUTOMATIC FIREARM

Walter T. Gorton, Springfield, Mass.

Application August 7, 1942, Serial No. 453,927

2 Claims. (Cl. 42—4)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to an improved bolt operating mechanism for an automatic firearm having a recoiling barrel.

It is an object of this invention to provide a bolt operating mechanism for an automatic firearm utilizing recoil and "blow-back" forces consecutively to obtain unlocking and opening of the bolt.

Another object of this invention is to provide a firearm bolt with a locking member which engages a suitable stop or shoulder on a fixed member attached to a barrel.

Another object of this invention is to provide a firearm having a short recoil movement of the barrel wherein the bolt is maintained in locked relation therewith during the initial recoil movement.

It is a further object of this invention to provide means for releasing the bolt locking member from its locked relation with the barrel by the recoil movement thereof thereby permitting the bolt to be opened by blow back action of the residual gas pressure.

The specific nature of the invention as well as other objects and advantages thereof will clearly appear from a description of a preferred embodiment as shown in the accompanying drawing in which:

Fig. 1 is a sectionalized view of the assembled operating mechanism for a firearm. In this view the moving parts of the mechanism are shown at the position of extreme recoil movement of the bolt.

Fig. 2 is a view similar to Fig. 1 however with the movable parts shown in their positions immediately after the pulling of the trigger.

Fig. 3 is a sectional view taken along the plane 3—3 of Fig. 2.

As shown in Fig. 1, in assembled relation, a barrel 1 is fixedly secured to a barrel extension 2, preferably by threads 1a. The barrel extension 2 shown in its preferred form is a long narrow rectangular member with rounded exterior corners. Longitudinal grooves 3 and 3a (Fig. 3) provided on the inside of the barrel extension 2, near the lower edge of the extension, slidably engage the ribs 4 and 4a of a receiver 5, which is not shown in detail but may be of any suitable conventional structure.

Provision is made within the extension 2 for housing a rectangular bolt 6. The bolt 6 is slide-

bly supported within the barrel extension 2 by the receiver 5 and is guided therein by ribs 7 and 7a of receiver 5, which engage suitable grooves in the bottom of bolt 6. In the bolt 6 a firing pin 9 is mounted for longitudinal movement within the axial firing pin hole 8 provided in bolt 6. A firing pin spring 10 surrounds the firing pin 9 and a retaining nut 11 holds the firing pin and spring within the firing pin hole 8. A bolt lock 12, preferably in the form of a rectangular bar, is hinged within a suitable recess in the bolt 6 by a transverse pin 13 which passes thru the hole 13a in bolt lock 12 and a suitable hole 6a in the bolt. The hinged end of the bolt lock 12 is formed as a semi-circular surface 12c having the transverse hole 13a as a center. This hinged end of the bolt lock fits snugly in a correspondingly shaped recess 13c in the bolt 6. The other end 12a of the bolt lock 12 projects beyond the end of bolt 6 for a purpose to be described. A weak spring 46 is inserted between the bolt lock 12 and the bolt 6 in suitable recesses 46a and 46b in the bolt lock 12 and bolt 6 respectively. This spring 46 exerts an upward force on bolt lock 12 and, in the closed position of the bolt 6, urges the bolt lock 12 into a correspondingly shaped recess 21 provided within the barrel extension 2. The end surface 21a of the bolt lock recess 21 is formed at such an angle as to provide positive locking of the bolt to the barrel extension when the bolt lock 12 is held up in bolt lock recess 21 by a bolt lock support 22 to be described later and yet to tend to cam bolt lock 12 out of locked engagement when bolt 6 is forced rearwardly with respect to barrel extension 2. The projecting end 12a of the bolt lock is shaped to correspond to the face 21a of recess 21 in barrel extension 2, so that when the bolt lock 12 is raised into the recess 21 the end or face 12a will snugly engage the face 21a of the recess 21, and the face 40 of bolt 6 will be the proper distance from the end 41 of barrel 1. This distance is commonly known as headspace. The lower corner 12b of bolt lock 12 is rounded to provide a suitable cam surface which assists in raising the bolt lock 12 into the recess 21 by camming action of a bolt lock support 22, as hereafter described.

As already stated the barrel extension 2 with barrel 1 secured thereto is slidably mounted on the receiver 5, the grooves 3 and 3a in the barrel extension 2 engaging the ribs 4 and 4a of the receiver. A bracket member 14 fits snugly around the barrel 1, abutting a shoulder 15 on barrel 1, and is securely held between the shoulder 15 on barrel 1 and barrel extension 2. An integral,

downwardly projecting lug 14a on the member 14 is provided with a suitable hole 14b which is engaged by a bolt 16 which bolt is secured to the receiver 5 by threads 20. A head 19 on the end of bolt 16 limits the forward movement of the member 14 and hence limits the forward movement of the barrel 1 and barrel extension 2. A spring 18 surrounding bolt 16 between an integral shoulder 17 on bolt 16 and the member 14 returns the barrel 1 and barrel extension 2 to the forward position as shown in Fig. 2 after their recoil movement has been completed.

A bolt lock support 22 is provided to assist in raising the bolt lock 12 to the locked position and to secure it therein. The bolt lock support 22 is a slotted member the lower end of which is hinged about a transverse pin 23, the pin 23 passing thru suitable holes in the support 22 and the receiver 5. The upper end of support 22 is rounded to a radius having the pin 23 as center, as shown at 22c, so as to continue to support the bolt lock 12 even when pivoted slightly counterclockwise about pin 23. A U-shaped torsion spring 24 is looped around pin 23 and the free ends inserted in suitable holes 25a and 25b in housing 5. The closed end of torsion spring 24 bears against the upper rear surface of support 22 biasing support 22 clockwise into an upright position. The rear face of bolt 6 acts as the stop for the support 22 when the bolt is in its closed position. Hence the support 22 acts somewhat as a follower with respect to the bolt.

A preferred form of bolt lock support and hammer is shown in Fig. 3 wherein the support is slotted to form two forklike members 22a and 22b. The slot formed by the forks 22a and 22b surrounds a hammer 26, which is pivotally mounted on the pin 23, and is of suitable shape to pass thru the slot formed by members 22a and 22b of member 22. One end of a hammer spring 28 is suitably attached to hammer 26. The other end of hammer spring 28 is supported on a conventional hammer spring strut 29. The hammer spring strut 29 is pivotally mounted on a transverse pin 30, which is mounted in the receiver 5. A sear notch 31 is provided on the bottom of hammer 26 to engage a sear 32 when the hammer is in the cocked position.

From the recoiled position the bolt 6 is returned to its forward position as shown in Fig. 2 by compressed operating spring 33, one end of which is inserted in a suitable recess in the rear of bolt 6 (not shown), while the other end slides over a guide rod 34. The guide rod 34 passes thru a suitable hole 35 in the rear of barrel extension 2 and extends into the extension 2 only a sufficient distance to properly support the driving spring 23. The guide rod 34 is secured within the extension 2 by the pin 36 which locks in a suitable recess when the rod 34 is turned approximately a quarter turn in either direction.

A bolt handle 37, comprising a knurled cylindrical portion 37a, which can be conveniently grasped by the fingers, and an integral straight shaft section 37b projecting inwardly therefrom, thru a suitable longitudinal slot in the barrel extension 2, (not shown) and into a suitable recess 6b in the bolt 6, is provided for manual operation of the bolt. The bolt handle 37 is secured within the longitudinal slot by any conventional means.

Firing is effected when the sear 32 is released from engagement with the sear notch 31 of hammer 26 by a conventional trigger mechanism (not shown) and the hammer, under the action of

hammer spring 28, strikes firing pin 9 and assumes the position shown in Fig. 2. The forward movement of the firing pin 9 caused by the hammer blow discharges a cartridge 38 in chamber 39 of barrel 1. The resulting explosion exerts a tremendous rearward pressure against the face 40 of bolt 6. However, as shown in Fig. 1 the bolt lock 12 is in the locked position and so held there by the bolt lock support 22. It is readily discernible that the rearward thrust caused by the discharge of the cartridge is transmitted through the bolt lock 12 to the shoulder 21 of the barrel extension 2, thus causing a rearward movement of barrel extension 2 and barrel 12 along the ribs 4 and 4a of housing 5. As the breech pressure at the moment of discharge of a cartridge in a firearm of the type herein described is exceedingly high, it is vitally necessary to maintain the bolt in locked relation with the barrel until the pressure in the chamber has been substantially reduced. Thereafter the bolt 6 is maintained in locked relation with the barrel extension 2 until the barrel extension 2 and barrel 1 recoil a predetermined distance, thus pivoting bolt lock support 22 slightly counterclockwise. By this time the pressure in chamber 39 has been appreciably reduced by the passage of the bullet 44 along the bore 43 of barrel 1 to a point where safe unlocking of the bolt can be effected. The initial recoil movement of the barrel extension 2 and barrel 1 also started a counter-clockwise rotational movement of the hammer 26 about the pin 23. The slight counterclockwise rotation of the bolt lock supporting member 22 results in withdrawal of positive support for the bolt lock 12. The residual pressure on the face of the bolt is still of considerable magnitude and by the camming action between surfaces 21a of the barrel extension and 12a of the bolt lock the bolt lock 12 is forced downward and out of engagement with the shoulder 21a of the barrel extension 2, thus unlocking the bolt and permitting it to fly backwards under the force of the gases. The bolt lock spring 46 is of course compressed by the downward movement of the bolt lock 12. The continued rearward travel of the bolt causes further rotational movement of the bolt lock support 22 and the hammer 26, thus stressing the bolt lock support spring 24 and hammer spring 28. Engagement of sear 32 in sear notch 31 is also effected. The rearward travel of the bolt also compresses operating spring 33 and is stopped when the bolt lock 12 contacts shoulder 45 on the barrel extension 2.

During the recoil movement of the barrel and barrel extension the projection 14, which is secured between the barrel and extension, also moves rearwardly and compresses spring 18 against shoulder 17 of bolt 16. At the completion of the recoil movement of the bolt the barrel and barrel extension are returned to the forward position by actuation of spring 18, the forward movement being limited by the stop 19. The compressed operating spring 33 drives the bolt 6 forward to its closed position shown in Fig. 2.

As the bolt 6 passes over the bolt lock support 22 the bias of spring 24 forces the support 22 to follow the bolt. The spring 46 biases the bolt lock 12 upwards into the recess 21 in the barrel extension 2 as the bolt closes, assisted by the camming action of bolt lock support surface 22c on bolt lock surface 12b. Support 22 rests against the rear of the bolt 6 and fully supports the bolt lock 12, thus locking the bolt mechanism.

to the barrel ready for the discharge of another cartridge.

The rifle described herein can readily be converted to continuous automatic fire as well as semi-automatic fire by the use of any suitable conventional trigger mechanism (not shown) whereby at will the sear 32 can be held depressed and out of engagement with the sear notch 31 after the discharge of the first cartridge, thereby allowing the hammer to follow the bolt on the closing stroke and automatically fire the succeeding cartridge. Release of the trigger permits the sear 32 to engage the sear notch 31 which holds the hammer 26 in the cocked position and prevents the discharge of another cartridge thereby causing the rifle to stop firing.

It should be understood that extraction and ejection of the previous empty cartridge case can be effected during the rearward movement of the bolt by any conventional extractor and ejector (not shown) provided on the bolt head. Feeding a new cartridge into the chamber 39 of barrel 1 is accomplished by the face 40 of bolt 6 picking up a cartridge from a conventional magazine (not shown) in the magazine well 47 and pushing it into the chamber 39 on the closing stroke of the bolt 6.

I claim:

1. An automatic firearm comprising a receiver, a barrel, a hollow extension secured to said barrel and mounted on said receiver for reciprocal movement, resilient means resisting rearward movement of the barrel with respect to the receiver, a bolt mounted on said receiver for independent reciprocal movement within said barrel extension, a firing pin mounted within said bolt and extending to the rear of the bolt, resilient means resisting rearward movement of the bolt, a rearwardly projecting latch pivotally secured to the top of said bolt, a latching surface on said barrel extension engageable by said latch when

the bolt is in battery position, a hammer pivotally mounted in said receiver beneath the bolt and adapted to engage the rear of the firing pin when the bolt is in battery position, a bifurcated follower surrounding said hammer and pivotally mounted to the receiver, said follower adapted to engage said latch when the bolt is in battery position to hold the latch in engagement with said latching surface thereby locking the bolt to the barrel until the barrel recoils a substantial distance with respect to the receiver, and resilient means biasing said follower forwardly.

2. An automatic firearm comprising a receiver, a barrel, a hollow extension secured to said barrel and mounted on said receiver for reciprocal movement, resilient means resisting rearward movement of the barrel with respect to the receiver, a bolt mounted on said receiver for independent reciprocal movement within said barrel extension, a firing pin mounted within said bolt and extending to the rear of the bolt, resilient means resisting rearward movement of the bolt, a longitudinal recess in the top of the bolt, a latch mounted in the recess having its forward end pivotally secured to the bolt and its rear end projecting beyond the rear of the bolt, resilient means biasing said latch upwardly, a recess in said barrel extension engageable by said latch when the bolt is in battery position, a hammer pivotally mounted in said receiver beneath the bolt and adapted to engage the rear of the firing pin when the bolt is in battery position, a bifurcated follower surrounding said hammer and pivotally mounted to the receiver, said follower adapted to engage said latch when the bolt is in battery position to hold the latch inserted in said recess thereby locking the bolt to the barrel until the barrel recoils a substantial distance with respect to the receiver and resilient means biasing said follower forwardly.

WALTER T. GORTON.
